UNITED STATES PATENT OFFICE.

RALPH H. GREEGOR, OF COLUMBUS, OHIO, ASSIGNOR TO THE KINNEAR MANUFACTURING COMPANY, OF COLUMBUS, OHIO, A CORPORATION OF OHIO.

WINDING AND COUNTERBALANCING MECHANISM FOR CURTAINS.

Application filed June 27, 1924. Serial No. 722,883.

To all whom it may concern:

Be it known that I, RALPH H. GREEGOR, a citizen of the United States, residing at Columbus, in the county of Franklin and State of Ohio, have invented a certain new and useful Improvement in Winding and Counterbalancing Mechanisms for Curtains, of which the following is a specification.

The object of the invention is to provide an improved hoisting and counterbalancing means for a door or curtain, especially where the opening to be closed is of unusual height such as is the case, for example, in marine towers for grain elevators. Owing to the horizontal form and dimension of such a tower and opening it is important to compact the hoisting and counterbalancing element as much as possible.

The invention is embodied in the example herein shown and described, the features of novelty being finally claimed.

In the accompanying drawing—

Fig. 1 is mainly a vertical sectional view on the line I—I, Fig. 2, showing a curtain winding drum equipped with a counterbalancing means according to my invention.

Fig. 2 is a sectional view on the line II—II Fig. 1, looking to the left and illustrating details of the counterbalancing means.

Fig. 3 is a diagrammatic sectional view showing a modification.

In the views 5 designates a stationary housing in drum form, the supporting frames 7 and 7^a thereof forming the inclosing heads or side walls. Journaled in said heads is a series of shafts 8 arranged in a circle each of which is equipped with a wheel 12 keyed thereto and having on its rim several eyes 13 any of which can be brought to coincide with an eye on a projection 14 on the head of the drum after which a pin 15 can be inserted through the two eyes to hold the shaft from rotation. Each shaft 8 has pinned to it at that end containing wheel 12, a collar 10 while loose on the other end is a spur gear 16 having a hub 8^a. Secured to each of the collars 10 and hubs 8^a at the opposite ends of a coil spring 9 so that when the spur gears 16 are turned in one direction the springs are placed under tension, such tension being re-

leased when said spur gears are turned in the opposite direction.

Journaled in suitable bearings in and between the supporting frame member or bracket 7 and an additional frame member or bracket 7^b is a shaft 6 on which are keyed the heads of a curtain receiving drum 5^a. The curtain referred to is indicated at 22 in Fig. 2. The shaft 6 has its axis coinciding with the center about which the shafts 8 and springs are arranged and said shaft projects at one end into the housing 5 where it has affixed to it a spur gear 17 arranged to engage and drive all the spur gears 16. The other end of the shaft 6 beyond the frame member 7^b has keyed to it a large spur gear 18 engaged by a smaller spur gear 19 keyed on a shaft 20 journaled in the frame member 7^b.

In the modification shown in Fig. 3 the parts are all substantially as shown and described except that the spur gears 16 are located outside the housing and said gears are driven by a spur gear 17^a on a shaft containing a spur gear 17^b of different diameter, this last named gear being engaged by a spur gear 17^c on the end of the drum shaft 6. As the diameters of the gears 17^b and 17^c can be indefinitely varied the ratio of tension increment of the springs 9 upon the unrolling of the curtain can be made to be what is desired. The increasing counterbalancing effect obtained by the springs can be at a rate substantially equal to or more or less than the weight of the unrolling portion of the curtain.

The operation, which can be readily understood from the foregoing description, is this: When the curtain is completely wound up the springs are so set that they exert zero or nearly zero pull but when the curtain is unwinding the drum shaft through spur gear 17 winds up the springs 9 thereby counterbalancing the weight of the unwound portion of the curtain or so much thereof as may be prearranged for depending upon whether the curtain is to be largely gravity actuated or otherwise. The power to operate the curtain is applied through the shaft 20 and as this power is applied it operates not only the curtain winding drum but also places tension upon or releases the tension from the counterbalancing springs.

The supporting frames 7 and 7^b present flanges for insuring the proper rolling of the curtain on the drum, said frames having guides at 23^a for the edges of the curtain.

The forms and arrangements of the parts can be changed without departing from the gist of the invention as claimed.

What I claim is:

- 10 1. A counterbalancing mechanism for a rolling curtain, including a winding shaft therefor provided with a spur gear fixed thereto, said counterbalancing mechanism including a frame, a spur gear mounted in the frame on an axis parallel to the axis of the curtain winding shaft and in position to be driven by the spur gear of the curtain winding shaft when the curtain is wound and unwound, a coil spring connected at one end with said second named spur gear to be wound and unwound when the curtain is unwound and wound respectively, said coil spring having its other end fixed to the frame.
- 15 2. A counterbalancing mechanism for a rolling curtain, including a winding shaft therefor provided with a spur gear fixed thereto, said counterbalancing mechanism including a frame, a spur gear mounted in the frame on an axis parallel to the axis of the curtain winding shaft and in position to be driven by the spur gear of the curtain winding shaft when the curtain is wound and unwound, a coil spring connected at one end with said second named spur gear to be wound and unwound when the curtain is unwound and wound respectively, said coil spring having its other end fixed to the frame.
- 20 3. A counterbalancing mechanism for a rolling curtain, including a winding shaft therefor provided with a spur gear fixed thereto, said counterbalancing mechanism including a frame, a plurality of spur gears mounted in the frame on axes parallel to the axis of the curtain winding shaft and in position to be driven by the spur gear of the curtain winding shaft when the curtain is wound and unwound, a coil spring connected at one end with each of said second mentioned spur gears to be wound and unwound when the curtain is unwound and wound respectively, said coil springs having their other ends fixed to the frame.
- 25 4. A counterbalancing mechanism for a rolling curtain including a winding shaft therefor provided with a spur gear fixed thereto, said counterbalancing mechanism including a frame, a plurality of spur gears mounted in the frame on axes parallel to the axis of the curtain winding shaft and in position to be driven by the spur gear of the curtain winding shaft when the curtain is wound and unwound, a coil spring connected at one end with each of said second mentioned spur gears to be wound and unwound when the curtain is unwound and wound respectively, said coil springs having their other ends fixed to the frame and means for adjusting the tension of each of said springs independently of the others.

tively, said coil spring having its other end adjustably fixed to the frame to regulate the tension thereof.

3. A counterbalancing mechanism for a rolling curtain including a winding shaft therefor provided with a spur gear fixed thereto, said counterbalancing mechanism including a frame, a plurality of spur gears mounted in the frame on axes parallel to the axis of the curtain winding shaft and in position to be driven by the spur gear of the curtain winding shaft when the curtain is wound and unwound, a coil spring connected at one end with each of said second mentioned spur gears to be wound and unwound when the curtain is unwound and wound respectively, said coil springs having their other ends fixed to the frame.

4. A counterbalancing mechanism for a rolling curtain including a winding shaft therefor provided with a spur gear fixed thereto, said counterbalancing mechanism including a frame, a plurality of spur gears mounted in the frame on axes parallel to the axis of the curtain winding shaft and in position to be driven by the spur gear of the curtain winding shaft when the curtain is wound and unwound, a coil spring connected at one end with each of said second mentioned spur gears to be wound and unwound when the curtain is unwound and wound respectively, said coil springs having their other ends fixed to the frame and means for adjusting the tension of each of said springs independently of the others.

RALPH H. GREGOR.
